35.

Daniel Hazzard

8514X

The Subscriber, informed to in this, Blackwell's Patent and Manufacturing part of the same, containing a description in the words of the said Daniel Hazzard himself of his improvement, beginning with or previous to, his application for patent. To all whom these presents shall come.

Be it known that I Daniel Hazzard of Philadelphia in the County of Philadelphia and State of Pennsylvania have invented a new and useful improvement in a machine for the use of invalids and the following is a full and exact description of the construction and operation of the said machine as invented by me, also denominated the Invalid Vehicle. The arrangement, adaptation and combination of certain parts of machinery (not in themselves new but formerly used for various purposes) thus forming by a combination of parts a new machine or engine never before constructed and thereby introducing a principle (like a soul in a body) and applying said principle through said engine to the bodies of invalids in their rooms houses or yards of their houses, so that they may derive the healthful (life giving) exercise (principle) that is usually received from riding upon the back of a trotting or walking horse, or in a two or four wheeler carriage. The base or lower part of this engine is formed by a pair of anchors in form nearly similar to the anchors attached to common working chairs only larger in all respects. The length of these anchors, forming said base, is three and a half feet each. They may be longer or shorter. The height of these anchors in their centers as they stand on the floor is six inches each, they may be higher or lower at their ends where they turn up and thereby form a sort of a neck. The depth from upper and under side is thirty

two inches at each end, or one and a half inch would be amply sufficient. Their thickness is one and three quarters inch, or they may be two inches in thickness. The rockers may be made of wood of any kind, perhaps Mahogany, any is as good as any other wood, or they may be made of metal. These rockers are fastened together near their middle by a piece of wood or iron, tenoned at each end and fitted into a mortise in each rocker and made fast by pins or screws. These rockers when connected together, ^{centred} and may be the same width or distance apart ^{at their} as above laid, are set ^{inches} apart at their front and back ends or they may be somewhat wider in front and narrower behind as it is usually the case with common rocking chairs. The piece with which they are connected at their center is six inches wide and two inches thick. These rockers as above described, form the base or ground work of the health vehicle. The next part or series of the same resting upon the rockers at or near their middle and fastened to them by substantial screws, with seats consist of three pair of elliptic springs made of steel. Three of these springs attached together at their middle, one above the other with a thin or thick inter- mediate substance (leather or wood,) by two screws at each middle with seats formed together with the rockers beneath, a spring leg; and both of them a pair of spring legs (the connected at their base by the six inch piece above laid) calculated to give a rolling or rocking motion or a per- cular motion according to the evolution of the invalid occupying the seat above, said elliptic springs which seat is now to be described. Upon these elliptic springs are thick lips and attached at their middle on each side by two substantial screws with seats set in the form of a chair without common legs, the spring legs coming in place of common legs, for the invalid to sit in and receive the ap- plication.

usage derivable from the vehicle. The form and dimensions of said chair ~~must~~ be such as the invalid wishes for, or can best occupy. Some cases of disease require one form, and some cases other forms - see drawing deposited in the patent office. These elliptic springs are similar in their form to those of the same name used by carriage manufacturers, but for this purpose as described above, they are found to answer best - when made of only four pieces of tempered steel each, say two of the pieces longer and connected together at their extremitie by screws, and two of them shorter and lying on the outside of the former longer pieces and made fast at their middle by a rivet in each. These pieces of tempered steel are, all of them, one quarter of an inch in thickness at their middle, and gradually become thinner towards their ends, say at their ends, in thickness, one eighth of an inch, or for a vehicle for a light person one twelfth of an inch in thickness; their width from end to end is the same, say one and three quarters inch. The longest and lowest of these springs is two and a half feet each, the next above is two feet three inches, and the next above (and last) is two feet - say in length all of them. These springs are set apart in their middle, each of them about five inches, while they come towards and connect together at their ends, at single spring attached to each so that might form a pair of spring legs for a light vehicle; but two, three or even five would be better in furnishing a much greater degree of elasticity and consequently a better motion. These steel springs when exposed to view have a coarse or unpolished appearance and should be covered with moleskin, or some other kind of stuff, in the form of drapery, but this latter is not absolutely necessary as it is only for appearance. The undersigned hereby certifies that

that he is the first person who has taken hold of the principle in idea, above named and embodied it so to speak, like a soul in a body, and manifested it in a manure-
gible, its effects self evident through the powers of the health
vehicle. He therefore hereby asserts his exclusive
claim to the aforesaid "principle" as well as the mode of apply-
ing it i.e. the health vehicle, being, as before said,
the first person who has successfully applied the same to
the alleviation or relief of the miseries of the human family
in all cases from the infant in the womb to the adult
of the age of one hundred years. The aforesaid "principle"
concerned for as above by the undersigned, he denominates
an operative cause terminating in successive activity
(of duration longer or shorter as may be successful) tending
to renovation of health, its life giving influence at-
tainable through the use of the health vehicle, within
doors, in any local situation under all the various cir-
cumstances of weather and climate. The same principle
tending to the same effect as above described and above
stated at in these words, "some cases of disease require one
form (of seat) and some cases other forms," has been em-
bodied by the undersigned by the adaptation and
application of the same spring legs and rockers to the
underside of the top part of a saddle, (Mans saddle
or Woman's saddle) resting on them at their tops (and
made fast to them with screws. These saddles to be used
in the same way, as when on the back of a horse. Also
the same spring legs and rockers have been adapted
and applied to a long seat resting on them at their tops
and fastened to them by screws, this latter to meet the case
of invalids who require a recumbent posture of the body. In
all of these forms, long men's or woman's saddle, longer the
the object of the undersigned had been to make the same

exercise (life giving principle) attainable by invalids of every description, from the bed ride to the sitting, walking, or riding invalid. On their application to a saddle the spring legs and rockers are brought nearer together, and in their application to a carriage they are extended further apart. Springs denominated elliptical or elliptical may be made of wood also of various substances besides steel, but such if made by another person, for the above described purpose would be considered an invasion of this specification and consequently of the rights of the under signed. Also gray hoppers springs, straight springs, (pieces) with intermediate pieces between them ex tremities operate on the same principle & are virtually the same. With elliptical springs in as much as they yield or give, from their centre towards their extremities alike. The mode of using this health vehicle is as follows. If the invalid sits in a chair resting upon the spring legs, if his strength will admit of it, a rapid motion of the arms in the way of swinging them say oblique or perpendicular will give to him through the aid of the vehicle a gentle or severe motion similar to the trot or rattle of a horse or the jolt of a carriage, according to his exertion, if he sits upon a saddle, the same exertion will produce the same effect, if however the case requires it a friend or servant must give the necessary exercise to the invalid by applying his hand or foot to the vehicle. If a lamp is used the aid of a friend or servant will be requisite to give through the vehicle the needed exercise. If an infant or child receives exercise from the vehicle, it must of necessity be through the aid of the nurse or some other person giving motion to the same.

Witness, Wm. Collingham Daniel Harrington
